UNITED STATES PATENT OFFICE

HENRY C. REUTER, OF CHICAGO, ILLINOIS

STORE-FRONT CONSTRUCTION

Application filed June 14, 1929. Serial No. 370,844.

This invention relates to window frame or store front constructions, preferably having a facing of bronze and a backing of wood or other suitable material. The invention may also be embodied in show cases and the like.

One object of the invention is to produce an attractive, strong and durable, but relatively inexpensive construction.

Another object is to produce a construction of the character described, wherein the outwardly facing members or pane-retaining strips of bronze are so shaped that they are particularly well adapted to receive an ornamental design on their outer surfaces. This is facilitated by arranging the co-operating inner and outer pane-engaging members in such manner that a relatively flat strip of bronze may be used for the outwardly facing member; as distinguished from the angularly shaped retaining strips of the prior art, of which my Patent No. 1,699,021 is an example.

Another object of the invention is to provide ventilating means which afford opportunity for circulation of air to prevent frosting and gathering of moisture on the window pane. The ventilating means herein disclosed are efficient and so arranged that the pleasing appearance of the window frame is not marred thereby.

In the drawings:

Figure 1 is a fragmentary view, in elevation, showing a corner of a window and frame embodying my invention.

Figure 2 is a vertical sectional view of the construction, showing a conventional store front window and above it a transom window.

Figure 3 is a horizontal section taken on the line 3-3 of Figure 2.

Figure 4 is a horizontal sectional view of the structure, arranged to show not only a straight wall embodying the invention, but also a right angle corner and other angles which may occur in store front constructions.

In that embodiment of my invention shown in the drawings, 5 indicates the masonry or other wall having an opening in which a window pane or window panes and frame work therefor are to be positioned. The window pane 6 is supported by a wooden strip or

backing 7 which is secured to the support 5 inwardly of the front surface of said wall 5. This strip 7 is cut away in its upper, front portion, to form a longitudinally extending shoulder 8, spaced from the pane 6, 55 for a purpose to be described.

Wooden strips 9 are provided to extend about the side and top margins of the pane 6, and these strips 9 are cut away to form the angular surfaces 10 and 11, one or both of 60 which may be provided with a longitudinal groove, such as shown in V-form on the surface 11.

Bronze strips 12 form the outer members of the frame and are secured to the wooden strips 7 and 9 by screws 13. These strips 12 of bronze are relatively flat and may be ornamented on their outer surfaces as indicated, by a rolling process. The inner surfaces are relatively flat excepting near the 70 longitudinal edges, where longitudinally extending grooves 14 are provided.

When the margins of the pane 6 are in place between the inner surfaces of the bronze strips 12 and the surfaces 11 of the wooden backing strips 9, there will be a small space between these parts, which is filled with putty 15 to hold the pane 6 securely in place. The grooves 14 and the V-grooves in the surfaces 11 provide locks for the putty 15. 80

Reverting now to the shoulder 8 on the wooden strip 7 which forms the lower support for the pane 6, said shoulder is spaced from the rear surface of the pane 6 to provide room for ventilating means and moisture drains. Said means include a long, relatively narrow and thin piece of metal, bent longitudinally to form an angle bar, having a vertically disposed front wall 16, rearwardly extending, horizontal wall 17, and a second vertical wall, located inwardly of the first, as indicated at 18, a forwardly and downwardly inclined wall 19, and a vertical pane-engaging wall 20, all integral with each other. 85

This angle bar is of a length equal to the width of the pane 6, and is positioned to have the front wall 16 between the bronze strip 12 and the backing 7, and the walls 17 and 18 resting against the cut away surfaces of the backing 7 and shoulder 8. 95

At intervals, say about one foot apart, the wooden strip 7 is cut away in its front portion to form vertically extending recesses, and at corresponding places, the wall 16 of the angle bar is bent inwardly into the cross-sectional form shown in Figure 3. These bent portions fit into the vertical recesses in the strip 7, and form vertical passageways 21 which communicate with the atmosphere through slots 22 in bronze strip 12. The slots 22 are cut in the strip 12 near its lower, longitudinal margin, one slot registering with each passageway 21. The inclined wall 19 of the angle bar is apertured as indicated at 23, and therefore, air may pass through the slot 22 upwardly through the passageway 21 and through the apertures 23 to ventilate the pane 6. Any moisture which may settle in the trough formed by the walls 19 and 20 of the angle bar will be drained by passing downwardly and outwardly through the passageway 21 and slot 22. The rubber cushions 24 between the pane 6 and wooden strip 7 do not interfere with the passage of air or moisture because they are spaced apart from each other and are not placed over the ends of any of the passageways 21.

It will be understood that the appearance of the structure is improved by having the ventilating and drain-opening 22 as near to the lower edge of the strip 12 as possible, and close to the masonry or other support 5, so as not to mar the appearance of the bronze 12, and therefore the passageway 21 is led to the slot in the lower longitudinal margin of the strip 12.

The upper pane 25 is similar to the pane 6 although usually smaller in area. It is mounted in a combination wood and bronze frame with ventilator means in that part which extends along the lower margin of the pane 25, just like that described in connection with the pane 6 except that the passageways 21 are eliminated. In arranging ventilation for the upper pane 25, the slots corresponding to the slots 22 are placed in that bronze strip 12 between the upper and lower panes, at the point indicated at 26. The angle bar used in connection with the pane 25, therefore, differs from the angle bar used for the pane 6 in that it is unnecessary to bend the wall 16 of the former because no passageway 21 is required. The air path, therefore, is from the slot 26, under the lower edge of the pane 25, between walls 17 and 19 of the angle bar, and through the apertures 23 of the latter; whereas in the frame construction for the pane 6, the air path is from slot 22, passageway 21, beneath lower edge of pane 6, between walls 17 and 19 of the angle bar, and then through apertures 23.

In Figure 4, a straight wall store front and various kinds of angular walls are shown in horizontal section; such as a right angle corner 27, and obtuse angles 28 and 29. The

bronze facing strips are all similar in that they are substantially parallel with the pane with which they co-operate and are substantially flat except near the margins where the putty lock-grooves 14 are formed. The wooden backing strips may be of any desired thickness and shape. They may be integral strips of wood cut away as indicated at 10 and 11 on Figure 2 or two pieces may be used as shown in the upper strip 9 above the window pane 25 in Figure 2.

Changes in details of construction may be made without departing from the scope of my invention.

I claim as my invention:

1. In store front constructions, a window frame including ventilating means, comprising a support extending across the frame, an outwardly facing, slotted, pane-retaining strip secured to the support and extending above the upper surface of the support, an angular bar in which a portion intermediate its longitudinal side margins is a wall horizontally disposed and resting on said support, and having a wall depending from the forward margin of the horizontal wall located between the retaining strip and support, a wall extending upwardly of the rear margin of the horizontal wall and then inclined downwardly and forwardly to form a chamber between said walls and the horizontal wall, said inclined wall terminating in a pane-engaging surface, the inclined wall being apertured, and the wall depending from said horizontal wall being bent inwardly to provide passageways extending from the slots in the retaining strip to the apertures of the angular bar.

2. In store front constructions and the like, a pane-receiving frame including outwardly facing pane retaining members of relatively thin metal, backing members positioned against the rear surfaces of the retaining members and secured thereto, a shoulder on each backing member extending longitudinally thereof and spaced from said rear surfaces of the retaining members to form a recess slightly greater in width than the thickness of the pane to be associated therewith, the retaining strip constituting the lower frame member being slotted at intervals, and ventilating means, located in the recess of the backing strip, comprising an angle bar bent longitudinally to form a pane-engaging member, an apertured wall extending rearwardly from the pane engaging member, walls extending downwardly and forwardly from said apertured wall to form a chamber between them and the apertured wall, and conduits connecting the chamber with the slots of the retaining member.

3. In store front constructions and the like, a pane receiving frame including outwardly facing, substantially flat metal strips, extending parallel with the pane to be held in

the frame, and surrounding the window opening, non-metallic backing members approximately as wide as said metal strips, secured to the metal strips, said backing members being cut away longitudinally at their window edges adjacent the metal strips to form a pane-receiving recess between the metal strips and backing members, the recess wall opposite the inner surface of said metal strip being parallel to the strip and spaced therefrom a distance slightly more than the thickness of the pane to be held by the frame.

4. In store front constructions and the like, a pane receiving frame including outwardly facing, substantially flat metal strips, extending parallel with the pane to be held in the frame, and surrounding the window opening, non-metallic backing members approximately as wide as said metal strips, secured to the metal strips, said backing members being cut away longitudinally at their window edges adjacent the metal strips to form a pane-receiving recess between the metal strips and backing members, the recess wall opposite the inner surface of said metal strip being parallel to the strip and spaced therefrom a distance slightly more than the thickness of the pane to be held by the frame, and said opposite proximate recess walls being grooved longitudinally.

In testimony, that I claim the foregoing as my invention, I affix my signature, this 8th day of June, 1929.

HENRY C. REUTER.
